UNITED STATES PATENT OFFICE.

SIMON M. O. BANGEN, OF CROOKSTON, MINNESOTA

PNEUMATIC STRAW-STACKER.

No. 921,341.

Specification of Letters Patent.

Patented May 11, 1909.

Application filed August 4, 1908. Serial No. 446,952.

To all whom it may concern:

Be it known that I, SIMON M. O. BANGEN, a citizen of the United States, residing at Crookston, in the county of Polk and State of Minnesota, have invented a new and useful Pneumatic Straw-Stacker, of which the following is a specification.

The invention relates to improvements in pneumatic straw stackers for threshing or separating machines.

The object of the present invention is to improve the construction of pneumatic straw stackers and to increase the efficiency of the same, and to provide a simple and comparatively inexpensive pneumatic straw stacker, adapted to be connected to an ordinary threshing machine or separator in position to receive the straw and chaff therefrom without the use of a conveyer or raddle rake, and capable of enabling the straw and chaff to be driven directly from the hopper into the chute without passing any portion of the material through the fan, whereby the pneumatic stacker may be operated at the expenditure of less power than those in which a portion of the material passes through the fan.

A further object of the invention is to arrange the fan out of the way of the material, so that there will be no liability of the cylinder teeth or other heavy objects accidentally getting into the fan casing and causing injury to the machine.

The invention also has for its object to arrange the fan at one side of the pneumatic stacker to enable its body to be raised higher above the ground than those fans, which are located either beneath or in rear of the hopper, and to permit a shorter fan shaft to be used, thereby lessening the material, and at the same time rendering the fan lighter in weight than heretofore.

Another object of the invention is to arrange the major portions of the eyes or air intake openings of the fan casing at the points where the fan starts to take in the air, and to gradually reduce the size of the eyes or air intake openings as the fan travels around, and to close the fan casing where the same is connected with the air trunk, and thereby enable the fan to drive the air into the air trunk more effectively and to increase the force of the air blast.

Another object of the invention is to con-

struct the hopper so as to cause the blast of air to travel along the bottom of the hopper from the nozzle or discharge end of the air trunk to the chute without producing interfering currents at the sides of the hopper.

A further object of the invention is to provide a pneumatic stacker equipped with means for enabling the sieves of the machine to be removed in the usual manner.

With these and other objects in view, the invention consists in the construction and novel combination of parts hereinafter fully described, illustrated in the accompanying drawings, and pointed out in the claims hereto appended; it being understood that various changes in the form, proportion, size and minor details of construction, within the scope of the claims, may be resorted to without departing from the spirit or sacrificing any of the advantages of the invention.

In the drawings:—Figure 1 is a perspective view of a pneumatic stacker, constructed in accordance with this invention. Fig. 2 is a reverse plan view. Fig. 3 is a longitudinal sectional view. Fig. 4 is a transverse sectional view, taken substantially on the line 4—4 of Fig. 3.

Like numerals of reference designate corresponding parts in all the figures of the drawings.

The pneumatic stacker is equipped with an approximately rectangular hopper 1, set at an inclination and having its upper portion arranged at an angle to the lower portion and forming a hood at the upper or rear end 2, which is curved downwardly for directing the material to the bottom of the hopper. The lower or front end 3 of the hopper is inclined upwardly and forwardly, and the bottom portion of the hopper is square in cross section, while the upper portion is laterally flared. The bottom 4, which is straight, is arranged at an inclination and extends upwardly and rearwardly from the mouth or nozzle 5 of an air trunk 6 to a cylindrical chute-receiving neck 7, which is located at the upper or rear end of the hopper. The lower portions 4^a of the sides of the hopper are parallel and are arranged perpendicular to the bottom of the hopper, and they coöperate with the same to form a contracted longitudinal bottom groove or channel. The upper and lower sections 8 and 9 of the upper laterally flared or inclined portions of the sides of

the hopper are arranged approximately at an angle of ninety degrees to the bottom of the hopper, and this inclination of the sides and the rectangular shape of the bottom portion of the hopper cause the blast of air to travel along the bottom of the hopper in a direct line from the nozzle or discharge end 5 of the air trunk to the cylindrical neck, and prevent the air from gliding upward and producing interfering currents at the sides of the hopper. The upper and lower sections of the flared upper portion are arranged at an angle to each other and are disposed at different inclinations, and the hood at the top of the hopper does not close any portion of the front of the same. The hopper, which is entirely open from the bottom to the top, is positioned to receive all of the straw and chaff from a threshing machine or separator without necessitating the employment of a conveyor or riddle rake, or carrying the material from the separator into the hopper.

The pneumatic stacker is designed to be connected with a separator in the usual manner, and the intervening space between the hopper and the casing will be covered in the ordinary manner with canvas, or other suitable material to confine the material to cause the entire discharge of the machine to fall into the hopper.

The neck 7, which is connected with the hopper below and in rear of the upper end 2, extends upwardly at an inclination and is adapted to be coupled to any suitable chute. Its outer portion is cylindrical for this purpose, and it gradually merges into the square bottom portion of the hopper.

The blast of air through the air trunk 6 is produced by a rotary fan 10, mounted on a horizontal shaft 11 and arranged within an approximately cylindrical fan casing 12, located at one side of the hopper and provided at the upper portions of its sides with approximately semi-cylindrical eyes or air intakes 13, arranged eccentrically with relation to the fan shaft and located at the front portions of the upper halves of the side walls of the fan casing. The air trunk 6 is connected with the fan casing at the bottom thereof and extends forwardly therefrom to a point in advance of the hopper, and it is provided therewith a return or upward bend forming the upwardly and rearwardly extending nozzle or mouth 5. The nozzle or mouth 5, which is set at an inclination, communicates with the hopper at the front end thereof, and its lower wall forms a continuation of the inclined bottom of the hopper. The air trunk is provided with a lateral bend 14, extending inwardly and forwardly to arrange the front end of the air trunk centrally with relation to the front or lower end of the hopper. The eyes or air intakes of the fan are so arranged that the casing is open where the fan takes in the air, and as the blades of the fan at the top

travel rearwardly, the eyes or intakes gradually close, and the fan casing is entirely closed at its lower portion to prevent the escape of air where the blades move forwardly for driving the air into the forwardly extending air trunk. This construction enables the fan to operate more effectively, and a stronger blast of air is thereby produced. The air travels upwardly through the air trunk to the front end thereof, and its direction is changed by the bend of the air trunk, and it enters the hopper through the inclined nozzle or mouth 5, and is practically confined in its operation to the inclined bottom channel or passage and formed by the lower portion of the hopper. The blast of air drives the straw and chaff up the inclined bottom of the hopper and through the chute, and as no portion of the material operated on passes through the fan, the pneumatic conveyor is adapted to be effectively operated with much less power than those pneumatic stackers, in which a portion of the material passes through the fan casing. Also the arrangement of the fan casing exteriorly of the hopper and in rear of the front end thereof effectually prevents cylinder teeth, or any other heavy object from coming in contact with the fan, and thereby causing injury to the machine. The arrangement of the fan at one side of the hopper enables the bottom of the fan casing to be raised higher from the ground than those fans, which are located in rear of or beneath the hopper, and the fan shaft does not have to be extended entirely across the hopper, thereby reducing the material and lightening the construction.

The fan shaft is journaled in suitable bearings or boxes 14^a, mounted on side beams 15 and 16, preferably constructed of flanged steel, or other suitable material. The side beam 16 is bent laterally to reduce the distance between the side beams to accommodate the fan casing, and they form a firm support for the same. The rear ends of the side beams are connected by a transverse end portion 17, which is fitted against the rear wall of the fan casing. The side beams are designed to constitute a portion of the framework for supporting the hopper. As the particular construction of the frame-work for supporting the hopper in an inclined position does not constitute a portion of the present invention, and as the hopper may be supported in any desired manner, illustration of the frame-work is deemed unnecessary. The bottom of the fan casing in practice will be equipped with a removable section or plate 18, adapted to permit the fan to be readily taken out when necessary.

The lower sections 9 of the upper portions of the sides of the hopper are provided with opposite doors 19, located adjacent to the upper sections 8 and extending downwardly from the upper edges of the sections 9. The doors

19 fit sufficiently tight in the openings provided for them in the sides of the hopper to prevent the escape of straw and chaff, and they are hinged at their lower edges 20 and 5 are secured in their closed position by suitable fastening devices 21, which may be of any preferred construction. The doors are adapted to permit the sieves of a separator to be removed in the usual manner.

10 Having thus fully described my invention, what I claim as new and desire to secure by Letters Patent, is:—

1. A straw stacker including a hopper set at an inclination and open from the front to 15 the rear wall and having sides flared outward at the upper portions and provided with lower portions coöperating with the bottom of the hopper and communicating with the same 20 throughout the entire length thereof, and means for forcing a blast of air through the bottom groove or channel.

2. A straw stacker including a hopper set 25 at an inclination and open from the front wall to the rear wall thereof, said hopper being provided with sides having outwardly flared upper portions, the lower portions of the sides being arranged perpendicular to the 30 bottom of the hopper to form a bottom groove or channel constituting the bottom of the hopper and communicating with the same throughout the entire length thereof, and means for forcing a blast of air through 35 the bottom groove or channel.

3. A straw stacker including a hopper set at an inclination and open throughout its entire length, said hopper having outwardly flared sides and being provided with a rear 40 end wall curved downwardly and rearwardly and forming a hood.

4. A straw stacker including a hopper set at an inclination and open throughout its entire length, said hopper being provided at its 45 bottom with a contracted longitudinal groove or channel and having a tubular extension or neck at the upper rear end of the groove or channel.

5. A straw stacker including a hopper set 50 at an inclination and open throughout its entire length, said hopper being provided at its bottom with a contracted longitudinal groove or channel and having a tubular extension or neck at the upper rear end of the groove or 55 channel, and a fan having an air trunk communicating with the lower front end of the groove or channel.

6. A straw stacker including a hopper set 60 at an inclination and open throughout its entire length and provided at its bottom with a contracted longitudinal groove or channel, said hopper having outwardly flared sides and provided with an upper or rear end wall forming a hood, said hopper being also provided in rear of the hood with an extension

or neck located at the upper rear end of the groove or channel.

7. A straw stacker including a hopper set at an inclination and open throughout its entire length and provided with sides flared at 70 their upper portions and having a lower inclined front wall and an upper rear wall extending downwardly and rearwardly to form a hood, said hopper being also provided at the bottom with a constricted longitudinal 75 groove, or channel, a tubular extension or neck arranged at the upper end of the groove or channel and located in rear of the upper end wall, and a fan having an air trunk communicating with the groove or channel at the 80 lower front end thereof.

8. A straw stacker including a hopper set at an inclination and open throughout its entire length, said hopper being provided at its sides with upper outwardly flared portions 85 composed of upper and lower angularly related sections disposed at different inclinations.

9. A straw stacker including a hopper set at an inclination and provided with a straight 90 inclined bottom and having sides, said sides being provided with angularly related upper and lower portions disposed at different inclinations, the upper portion of the hopper forming a hood entirely open at the front. 95

10. A straw stacker including a hopper set at an inclination and open throughout its entire length and having outwardly flared sides, said sides having oppositely disposed doors located intermediate of the ends of the 100 hopper.

11. A straw stacker including a hopper, a fan located at one side of the hopper at a point intermediate of the ends thereof, and an air trunk extending forwardly from the 105 fan to the front end of the hopper and communicating with the said front end.

12. A straw stacker including a hopper, a fan located at one side of the hopper at a point intermediate of the ends thereof, and an air trunk extending forwardly from the 110 fan to the front end of the hopper and communicating with the same centrally of the front end at the bottom of the hopper.

13. A straw stacker including a hopper, a 115 fan located at one side of the hopper at a point intermediate of the ends thereof, an air trunk extending forwardly from the fan and bent laterally to arrange its front end centrally with relation to the median line of 120 the hopper, said air trunk being provided at its front end with a rearwardly extending nozzle or mouth communicating with the front of the hopper.

14. A straw stacker including a hopper, a 125 fan located at one side of the hopper at a point intermediate of the ends thereof, an air trunk extending forwardly from the fan and bent laterally to arrange its front end centrally with relation to the median line of 130

the hopper, said air trunk being provided at its front end with a rearwardly extending nozzle or mouth communicating with the front of the hopper and arranged at an inclination.

15. A straw stacker including a hopper provided with a contracted longitudinal bottom channel or groove, a fan arranged at one side of the hopper, an air trunk extending forwardly from the fan to the front end of the hopper and having a rearwardly extending nozzle connected with the front end of the bottom groove or channel.

16. A straw stacker including a hopper provided with a contracted longitudinal bottom channel or groove, a fan arranged at one side of the hopper, an air trunk extending forwardly from the fan to the front end of the hopper and having a rearwardly extending nozzle connected with the front end of the bottom groove or channel, and a tubular extension or neck arranged at the upper rear end of the groove or channel.

17. A straw stacker including a hopper, a fan provided with a casing having an eye or intake located at the upper portion of the side of the casing and arranged eccentrically

with relation to the fan, said casing being closed at the lower portion, and an air trunk extending from the lower closed portion of the casing to the hopper.

18. A straw stacker including a hopper, an air trunk connected with the hopper, and a fan having a casing connected at the bottom with the air trunk, said fan being also provided at the upper portion of its sides with an eye or air intake arranged eccentrically with relation to the fan and tapered rearwardly.

19. A straw stacker including a hopper set at an inclination, a fan having a casing arranged at one side of the hopper at a point intermediate of the ends thereof, and an approximately horizontal air trunk connected with the fan and extending forwardly therefrom to the front end of the hopper, the front portion of the air trunk being located beneath the hopper.

In testimony, that I claim the foregoing as my own, I have hereto affixed my signature in the presence of two witnesses.

SIMON M. O. BANGEN.
